UNITED STATES PATENT OFFICE.

MAX KRAUSE, OF CHICAGO, ILLINOIS.

UPHOLSTERY CONSTRUCTION.

Application filed May 31, 1924. Serial No. 716,852.

The present improvements relate to means for carrying the weight imposed upon the seat of a chair, lounge, davenport, and similar articles of furniture. Its chief objects are to provide in upholstery construction greater wearing qualities, longer life in service, and greater safety to the occupant and to the materials employed, and to accomplish such advantageous results by simple means. Other objects and advantages will appear hereinafter.

It is old to provide supporting means for metallic slats or straps at the ends thereof, or for wires at the same relative place in the upholstery construction, as witness the patents to Staples 534,844 of February 26, 1895, and 531,477 of December 25, 1894, and the patent to Foster 529,485 of November 20, 1894. The present improvements are with respect to flexible fabric webs as distinguished from metallic supports for the springs.

In the accompanying drawings, which form a part of this specification, Figure 1 is a fragmentary sectional view showing a preferred form of the improvement as applied for use; Fig. 2 shows the structure of Fig. 1 before the web-tightening-and-holding element is driven into the frame; Fig. 3 is a bottom plan on a smaller scale showing the elements of Fig. 1; Fig. 4 is a sectional view as on the line 4—4 of Fig. 1; Fig. 5 is a perspective, on an enlarged scale, of the web-holding element shown in the previously mentioned figures; Fig. 6 is a sectional view taken on the line 6—6 of Fig. 7 showing a modified construction; Fig. 7 is a bottom plan of the parts of Fig. 6; Fig. 8 is a view similar to that of Fig. 4, but showing another modified construction, and being taken on the line 8—8 of Fig. 9; Fig. 9 is a sectional view on the line 9—9 of Fig. 8; Fig. 10 is a perspective of another form of holding device; Fig. 11 is a bottom view showing the usual and well-known method of attaching the fabric webs to the frame; and Fig. 12 is a sectional view on the line 12—12 of Fig. 11.

In upholstery construction for seats, it is ordinary and well-known practice to provide a plurality of parallel longitudinal webs 15 and a plurality of parallel transverse webs 16, the two series of crossing webs being interwoven or interlaced, as well shown in Fig. 3. In certain of the constructions a separate wooden frame is provided, which may be rectangular or have some other shape

as called for by the shape of the seat or back of the upholstered article, the frame being open at top and bottom. Such frame parts are marked 17 in the drawings. In 60 lieu of such separable frame the structure of the chair or other article may constitute the frame. In old practice, as shown in Figs. 11 and 12, the fabric webs are folded at their ends and simply nailed to the frame, 65 as by relatively long nails 18, the webs having first been drawn as taut as reasonably possible.

The webs 15 and 16 constitute supporting elements for a plurality of springs 19, and 70 at the other ends of these springs there is padding and a finishing piece of fabric, not shown but well understood.

The weight of the person is therefore communicated through the springs to the 75 webs 15 and 16. According to the old practice, as shown in Figs. 11 and 12, this pressure is communicated to the nails, as 18, substantially in the direction of the nails. The oft-repeated pressures upon these nails 80 works them loose, especially after the wood of the frame dries out. Another objection is that these relatively long nails driven into a relatively narrow frame cause the wood to split whereby the nails become loose. For 85 various reasons, after one series of nails has been driven into the frame at a given place the repair job by adding additional or other nails is unsatisfactory. The old construction does not provide the desired strength and 90 security, freedom from the necessity of repairs, or length of life of the parts in service.

According to the present improvements the objection to the old practice is overcome to a very notable extent through the provision of a web-holding element which relieves the nails of much of the strain upon them and changes the direction of such strains to one normally at right angles to 95 the direction of the nails, thus avoiding their pulling out, and at the same time permitting the use of much smaller nails, saving the frame from objectionable splitting, and also making the webs more taut.

The simplest and preferred form of the present improvements is shown in Figs. 1 to 5 inclusive, in which the web holder or hanger 20 is shown as substantially U-shaped piece of iron or steel wire having a part 20^a and two upstanding end parts or legs 20^b, each having a spike element 20^c

extending substantially at right angles to the legs 20^b respectively. The thickness of this wire will vary according to the strength desired, but in ordinary practice ordinary iron wire one-eighth of an inch in diameter will be found satisfactory. The length of the part 20^a is preferably such that the web as 16 will conveniently fit between the legs 20^b, as well shown in Fig. 4, and lie on the normally under surface of the web. I find that a length of about one and one-quarter inches for the legs 20^b is satisfactory, but their length may vary. The spikes 20^c may well be three-fourths of an inch in length, but for a relatively thin frame part they could be shortened.

To apply the structure 20 the preliminary steps may be taken as in old practice, except that the nails 21 may be considerably smaller than ordinarily employed, and may be ordinary tacks of about the size known as carpet tacks. The member 20 is then applied as shown in Fig. 2, (before the springs 19 are positioned, however) and the member 20 having been drawn upward so that the part 20^a is snug and tight against the fabric the spikes 20^c are driven into the wood and then occupy the position shown in Fig. 1. The effect of driving the spikes into the wood is to draw the part 20^a upward, tautening the web. To prevent undue wear upon the fabric the lower inner corner of the frame 17 is rounded at 22. The result of the application is that the web has been tightened quite materially, and at the same time an element has been interposed which takes much of the downward strains and converts the pull upon the nails as 21 into a right angled pull as mentioned. Instead of extending directly inward, the web is made to extend upward a short distance along the lower inner corner portion of the frame and then inward, the web being given what may be termed a compound bend, as well seen in Fig. 1, and the normally downward strains upon the web are first taken by the holder or hanger and then by the nails holding the web upon the lower edge surface of the frame. The downward pull upon the hanger is at substantially right angles to the spikes 20^c, making for great strength and security of construction.

In order to insure the spikes 20^c against working out such locking provisions as barbs shown in Fig. 5 may be provided.

Referring to Figs. 6 and 7 the construction of the hook element 24 is substantially the same as shown in Fig. 5. A sheet-metal clip 25 having two parts adapted to be sprung apart for insertion of the holder 24, and adapted to lie upon the fabric at the wood affords protection for the fabric and cooperates in holding the fabric. The substantially tubular part 26 of the clip contacts the fabric and draws it tighter when

the spike is driven home. The effect of this construction is to cause the strains upon the nails as 27 to be at right angles to their direction respectively, and, as in the structure of Fig. 1, to provide an intermediate device adapted to hold the fabric in a given position at the lower portion of the frame, avoiding all sagging there and providing a strong and permanent holding element adapted to take much of the strain, and to provide a firm, safe and secure connection.

Referring to Figs. 8 and 9, a construction is there illustrated according to which a relatively long rod 30 serves as the support for the fabric and this rod is held in position by clips 31 spaced apart preferably the width of the fabric web and secured as by nails 32 to the frame 17. In a long structure like a davenport the single wire or rod 30 may extend the full length of the seat. When it is desired to take the structure apart this rod may simply be drawn out of the clips 31 and the relatively short nails 33, Fig. 9, pried out. The nails 32 hold the clips 31 strongly to the frame so that the downward pressure is communicated strongly to them, and at right angles to their direction, and the strains upon the fabric are communicated at right angles to the direction of the nails 33 also. The fabric web 16 may be tightened by the drawing effect of the nails as they are applied.

In Fig. 10 I have shown a structure comprising a wire link 25 upon which are positioned two clips 36 and 37, these clips being respectively like the clips of Figs. 6 and 7. This device is applied in part as shown in Figs. 6 and 7, while the upwardly extending clip 33 takes the place of the spike-ended holder 24. The strains of service are similarly communicated to the attachment device, and these strains are at all times in a direction at right angles to the direction of the nails passing through the holes 39 and 40 shown.

The construction of this attachment, in any of the forms illustrated, is exceedingly simple and cheap, very easily applied, and through its use an unusually strong construction is effected, to the end that the expense and annoyance experienced with the construction of Figs. 11 and 12 are overcome and the life of the parts in service is greatly increased.

It is to be understood, of course, that the holding member is applied to each of the webs where secured to the frame, and that the webs extend across the open bottom of the frame and are secured to it at each end of the web sections respectively.

I contemplate as being included in these improvements such modifications of and departures from what is herein specifically illustrated and described as fall within the scope of the appended claims.

I claim:—

1. In upholstery construction of the character described, the combination of a frame part, a flexible fabric web secured to the normally under surface of the frame, and auxiliary supporting means for the web comprising a member secured to the frame and passing across the web on its normally under surface adjacent to the frame and holding the web in normally raised position at the lower edge of the frame where the web extends inward therefrom and converting downward strains applied upon the web at places inward of the frame into upward strains upon the web where it extends between the lower surface of the frame and said supporting means.
2. In upholstery construction of the character described, the combination of a frame part, a web secured to the normally lower edge portion thereof, and means for drawing the web normally upward above the inner lower edge portion and holding the web so that it extends first upward from the lower inner edge portion of the frame 25 and then substantially at right angles to the frame.
3. In upholstery construction of the character described, the combination of a frame part, a plurality of webs of the character described having their respective ends secured as by nails or the like to the normally bottom edge of the frame and extending inward therefrom in the same general direction, and a web-holding member 30 including a rod on the under surfaces of said webs respectively closely adjacent to the frame, with rod-holding clips at intervals secured to the frame and arranged to hold said rod in a relative position at the 35 frame to convert the pull upon the nails or the like to one substantially at right angles to the direction thereof respectively.

MAX KRAUSE.
